US0D1106118S

(12) **United States Design Patent** (10) **Patent No.:** **US D1,106,118 S**
Garlington (45) **Date of Patent:** **** Dec. 16, 2025**

(54) **WEARABLE ACCESSORY INCORPORATING NEAR FIELD COMMUNICATION TECHNOLOGY**

(71) Applicant: **Contact Wearables LLC**, Midland, TX (US)

(72) Inventor: **Nathanael Garlington**, Midland, TX (US)

(**) Term: **15 Years**

(21) Appl. No.: **29/883,620**

(22) Filed: **Feb. 1, 2023**

(51) LOC (15) Cl. **14-02**

(52) U.S. Cl.

(57) **CLAIM**

The ornamental design for a wearable accessory incorporating near field communication technology as shown and described.

DESCRIPTION

FIG. 1 is a front top perspective view of a wearable accessory incorporating near field communication technology, showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is an exploded view thereof; and,

FIG. 9 is a cross section view thereof, taken in the direction of line 9-9 as seen in FIG. 6.

1 Claim, 9 Drawing Sheets
